ADJUSTABLE LADING STRAPPING ANCHOR

Frank H. Pietzsch, Clayton, Mo., assignor, by mesne assignments, to Thrall Railway Devices Company, St. Louis, Mo., a corporation of Missouri

Application August 4, 1954, Serial No. 447,870

1 Claim. (Cl. 105—369)

This invention relates to lading strapping anchor means and particularly to anchor means of adjustable character for use in freight vehicles.

An object of this invention is to provide an improved anchor means which can be adjusted relative to the usual mounting means or posts in the freight vehicle to adapt itself to tolerances or variations which occur during construction of the vehicle in which the anchor means are placed.

It is an object to simplify the number and form of the parts constituting the lading strapping anchor means so that the adjustment features thereof may be attained more economically.

It is also an object to provide an improved and simplified anchor means which will effectively fit into the walls of the freight vehicle without creating holes or gaps which are objectionable and limit the general usefulness of the vehicle.

These and other objects and advantages will be pointed out in more detail in connection with the disclosure of adjustable anchor means herein preferred.

The present invention broadly consists in lading strapping anchor means secured in adjustable relation upon the vehicle side wall column members, with the anchor means including a body having a strap engaging bar and a recess thereadjacent, and marginal projections about the body to engage with tongue and groove type lining boards whereby an effective seal is formed to prevent vehicle infestation from the result of unclean vehicles.

The present invention further and more specifically consists in base members adapted to be secured to the usual column members of the freight vehicle wall assembly in predetermined spaced relation along the length of such column members, and anchor means adjustably attached or engaged on the base members and adapted to fit with the usual vehicle wall lining boards. The invention also may consist in the provision of anchor means directly and adjustably engaged upon the usual column members and adapted to fit with the lining boards for the vehicle walls. The invention further consists in adjustable anchor means varying from the foregoing in the details of form and construction, but embodying the principles hereof.

The invention in certain forms is disclosed in the accompanying drawings, wherein:

Fig. 1 is a fragmentary perspective view of a portion of the vehicle wall column assembly and wall lining boards showing the present lading strapping anchor means,

Fig. 2 is a fragmentary and enlarged front view of the lading strapping anchor means of Fig. 1,

Fig. 3 is a transverse sectional view of the lading strapping anchor means as seen along line 3—3 in Fig. 2,

Fig. 4 is a longitudinal sectional view of the anchor means as seen along line 4—4 in Fig. 2,

Fig. 5 is a fragmentary front view of another form of lading strapping anchor means,

2

Fig. 6 is a longitudinal sectional view of the anchor means seen along line 6—6 in Fig. 5,

Fig. 7 is a transverse sectional view of the anchor means seen along line 7—7 in Fig. 5,

Fig. 8 is a fragmentary front view of a further form of lading strapping anchor means,

Fig. 9 is a transverse sectional view of the anchor means seen along line 9—9 in Fig. 8,

Fig. 10 is a longitudinal sectional view of the anchor means seen along line 10—10 in Fig. 8,

Fig. 11 is a fragmentary transverse sectional view through still another form of the present lading strapping anchor means,

Fig. 12 is a longitudinal sectional view of the lading strapping anchor means of Fig. 11 as seen along line 12—12 thereof,

Fig. 13 is a fragmentary transverse sectional view through yet another form of the lading strapping anchor means of this invention,

Fig. 14 is a longitudinal sectional view of the anchor means of Fig. 13 as seen along line 14—14 thereof,

Fig. 15 is a fragmentary front elevational view of a vehicle wall column member adapted to receive lading strapping anchor means of the form shown in Fig. 13,

Fig. 16 is a fragmentary front elevational view of a vehicle wall column member adapted to receive lading strapping anchor means of the form shown in Fig. 11,

Fig. 17 is a transverse sectional view of the column member shown in Fig. 16 as seen along line 17—17 thereof, and

Figs. 18 and 19 are respectively a fragmentary front elevational view of a modified column member adapted to receive an anchor means of the form shown in Fig. 11, and a transverse sectional view along line 19—19 of Fig. 18.

With reference to Figs. 1 to 4, the lading strapping anchor means is shown on the usual metal column member formed with an inner flange 11, an outer flange 12 and a connecting web 13. The column 10 is usually associated with a nailing post 14 located adjacent the web 13 and outer flange 12. The column and post assembly are duplicated at spaced intervals along the vehicle walls, and the same are enclosed by a suitable outer wall sheeting 15 (Fig. 3). A typical vehicle wall construction of this character may be better understood upon reference to Patent No. 2,610,587 issued to Frank H. Pietzsch on September 16, 1952.

The inner sheathing of such a freight vehicle may, as in the present invention, consist of a plurality of boards 16 certain of which are secured to the nailing posts 14 by suitable means 17. Each of the boards 16 may be of tongue and groove type in which the tongue 18 along one edge fits into a groove 19 along the adjacent edge of another board 16, as is well understood.

The lading strapping anchor means shown in Figs. 1 to 4 includes a base member 20 having a curved or recessed face 21 terminating at two opposite margins in wing tabs 22. The other two margins are adapted to be welded, as by the weld material 23, to the face of column flange 11 at a predetermined place along the vertical length thereof. A plurality of these base members 20 may be spaced along the column flange 11 to receive the anchor bodies 24 in vertically adjustable fitted relation.

Each anchor body 24 consists in a casting or otherwise shaped member having a thickness substantially equal to the thickness of the boards 16 so as to fit flush with such boards (Fig. 1).

The anchor body 24 is provided with a lading strap engaging bar 25 set flush with the front face and flanked on opposite sides by openings 26 which afford access behind the bar 25. The rear face of the body 24 is open between the vertical body portions 27 (Fig. 3), and in-

wardly directed tabs 28 are formed on each body portion 27 to engage and slide behind the wing tabs 22 on the base member 20. The upper and lower margins of the face openings 26 in the body 24 are formed with inwardly directed flanges 29 (Fig. 4), the flanges 29 being extended behind the bar 25, as shown in Fig. 2. The upper margin of the body 24 has a projecting tongue 30, and each vertical side margin has a similar projecting tongue 31, all as shown in Figs. 1, 3 and 4. The lower margin of the body 24 is formed with a front projection 32.

In assembly and after an appropriate number of the individual base members 20 have been welded to the column flange 11, the lining boards 16 are laid up from the vehicle floor in the normal manner of tongue and groove boards with securing means 17 engaging the nailing post 14. As the boards reach a base member 20 one of the bodies 24 is slipped over the wing tabs 22 with the body tabs 28 (Fig. 3) slidably engaging the same. The body 24 is moved downwardly so that its lower projection 32 fits over the adjacent board tongue 18 to form a sealed joint. Since the body member 24 has substantially the same width as the lining boards 16, the boards falling in horizontal alignment therewith must be end grooved, as at 33 (Figs. 1 and 3), to receive the projections 31 so that a sealed joint is formed. The next or top board 16 may then be laid up with its groove 19 engaged by the tongues 18 and body projection 30 to form a sealed joint.

The advantage with the described assembly is that the body 24 lies flush in the wall lining boards and its margins are fully sealed with these boards so as to be vermine proof and capable of retaining bulk lading out of the wall spaces when needed.

Since the body 24 has the openings 26 at each side 35 of the bar 25, it is formed to fit about the base 20 so that the face 21 of the base 20 acts as a guide to conduct the end of a lading strap (not shown) into and out of the space (Fig. 3) behind the bar 25. Also, body portions 27 closely fit with the base wing tabs 22, and in-turned flanges 29 on the body 24 are formed to fit with the face 21 of the base 20, to seal off the open rear area of the body 24. Another advantage of this form of the invention is that the body 24 may be moved relative to the wing tabs 22 on base 20 to accommodate variations in the lining boards 16 and yet retain a strong engagement with the base which resists the pull exerted by a lading strap upon the bar 25.

Another form of this invention is shown in Figs. 5, 6 and 7. The base member 35 comprises a plate having the side flanges 36 (Fig. 7), longitudinal margins 37 (Fig. 6), and outturned and reversely directed wing tabs 38 which are formed in the process of forming a central opening 39 therein. This opening 39 exposes a portion of the column flange 11 so that weld material may be deposited therein to fix the base on the flange 11.

A modified body 40 is used with the base 35 as, as before pointed out, the body 40 has a front face provided with an integral recessed portion 41 which is substantially rectangular in the view of Fig. 6 and curved in the view of Fig. 7. The curved form of this recessed portion 41 provides access behind a lading strap engaging bar 42 which has its ends welded to the body 40 (Fig. 6). Body 40 is also formed with side projections or flanges 43 which are spaced opposite base flanges 36 to receive the projecting rabbeted end portions 44 of the boards 16. The longitudinal margins of body 40 are also formed at the upper side with a projecting tongue 45 to engage a board groove 19 and at the lower side with a right angular flange having the flange portions 46 and 47 adapted to engage with a board tongue 18. The rear face of body 40 adjacent the side flanges 43 is formed with mounting tabs 48 which are adapted to slidably engage with the base tabs 38 upon mounting the body.

The assembly of the modified base 35 and body 40

75

is carried out as described for the form of this invention described in Fig. 1, and the advantages thereof are similar.

A further form of this invention is disclosed in Figs. 8, 9 and 10. The anchor means hereof comprises an integral body 50 having a centrally curved recessed portion 51 between upper and lower facing portions 52. The portions 52 are provided with openings 53 to receive securing means 54 which extend rearwardly through vertically elongated apertures 55 in the column flange 11. Threaded holding means or nuts 56 engage the means 54 for clamping the body 50 in position of adjustment vertically along flange 11. In the previous forms the body was mounted on the column flange by base means fixed to the flange. The present anchor means includes the body 50, but the base means now is considered to be the means 54 which still performs the securing function as before. Now base means 54 which secures body 50 can move relative to the column flange without detracting from the adjustability of the anchor means as a whole. Thus the underlying principles hereof are not altered to any great extent.

The body 50 is formed with an upper projecting tongue 57 to fit with board groove 19, a lower marginal groove 58 defined by the front and rear projections 58', and opposite side spaced projections or flanges 60. The groove 58 has a central boss or obstruction 59 required for the means 54. The boss 59 requires that the tongue 18 be cut away at 61 to assure the sealed fit, and spaced flanges are adapted to receive the rabbeted ends 44 of the boards 16 which abut the sides of the body 50. The assembly of body 50 is carried out in accordance with the principles described for the anchor means of Fig. 1.

Since the foregoing sets forth the details of form and assembly of certain forms of the present invention, the following modifications will be described in relation to sectional views thereof.

In Figs. 11 and 12, the anchor means comprises a base 62 of flat plate form secured to the column flange 11 by welding at 63 along opposite margins. The base has opposite tabs 64 which project beyond the longitudinal side margins of flange 11, past 14' being rabbeted at 65 to receive the flange and other means also. The body 66 is an integrally formed part having a curved recessed face 67 framed between side margins 68. A lading strap engaging bar 69 is secured in the recess flush with the face of the body and between the side margins 68. The side margins of body 66 are formed with front projections or flanges 70 (Fig. 11) and rear projections or flanges 71 spaced by body side walls 72. Body side walls 72 also carry inwardly directed tabs 73 which are adapted to slidably engage the tabs 64 on the base 62 upon mounting the body upon the base. Upper body margin (Fig. 12) is formed with a projecting tongue 74 fitting with a board groove 19, and lower body margin is formed with a front projection or face flange 75 which abuts a board tongue 18. Thus, the body 66 has a sealed fit along its margins with the upper and lower boards, and the side flanges 70 and 71 fit with the adjacent rabbeted ends 44' of boards 16.

The modified form of anchor means disclosed in Figs. 13, 14 and 15 includes a body 77 having a curved recessed face 78 framed between side margins 79. A lading strap engaging bar 80 is secured in the recess flush with the body face and between the side margins 79. The body side walls 81 are formed with front projections or flanges 82 and rear projections or flanges 83. The side walls 81 each have inwardly directed tabs 84 which are rearwardly off-set relative to flanges 83. The upper margin of the body 77 is provided with a projecting tongue 85 adapted to fit with the groove 19 in a lining board. The lower margin is provided with a front projection or flange 86 to abut a lining board tongue 18.

The body 77 of Figs. 13 and 14 is adapted to be mounted on a vehicle column member of modified form.

The column is provided with an outer flange 87, a web 88 and an inner flange 89 including a marginal tab edge 90 engaged by one of the body tabs 84 and by an opposite tab edge 91 extending adjacent the web 88 to be engaged by the opposite body tab 84. A nailing post 92 is set adjacent the column flange 87 and web 88, and is rabbed at 93 to receive the body tab 84 and flange 83. In Fig. 15, the column has its tab 91 cut away at the top to form a notch 94 which permits the bodies 77 to be moved into position where the respective tabs 84 may be passed behind the column tabs 90 and 91 preparatory to sliding the bodies downwardly on the column until they are fully engaged, as shown by Fig. 13. The lining boards 16 may then be placed, with certain of the boards provided with rabbed ends 44' to be embraced between the body flanges 82 and 83.

The advantage of the last described anchor means resides in its greater flexibility of assembly, as the mounting base is formed by the column flange 89 directly. This allows an infinite adjustment of the bodies 77 along the column so that lining boards of variable widths may be employed with ease.

Figs. 16 and 17 disclose a modified column useful with the bodies 66 disclosed in Fig. 11. The usual Z-shaped column, having outer flange 95, web 96 and inner flange 97, is provided with a full length base plate 98 which is wider than the inner flange 97 to form marginal tabs 99 at each side of the flange 97. The upper end portions of the marginal tabs 99 are cut away to form notches 100 which permit slidable assembly of the bodies 66 from the notches 100. The assembly procedure has been detailed in connection with the disclosure of Fig. 15.

Figs. 18 and 19 disclose a further modified column which may be used in place of the column described in Figs. 16 and 17. The modified column is of H-shape having an outer flange 101, a web 102, and an inner flange 103. The upper end portion of flange 103 at its side margins is notched at 104 to permit slidable assembly of anchor bodies of the forms shown at 66 and 77 respectively in Figs. 11 and 13.

It should now be apparent that in each form of the invention disclosed herein the anchor means is securely engaged to withstand lading strain through the strap engaging bar means. Such strain is passed into the adjustable bodies and thence to the vehicle wall column members. The bodies and base members, whether attached to or integral with the columns, fully seal off the interior wall space from the vehicle interior so that bulk lading may be transported interchangeably with package or crate lading. The anchor means being sealed at all points prevents vehicle infestation as thorough cleaning of bulk lading remains can be assured. It is further pointed out that the present forms of anchor means will provide an adjustment of the anchor body along the columns so that economies of vehicle construction or repair may be realized.

What is claimed is:

In a lading transporting vehicle, in combination, a

structural column having a vertically extending flange including a flat face having opposite vertically extending edges, a plurality of wall boards having tongue and groove connections with one another and disposed in engagement with said flat face to define a wall sheath abutting said flange, said wall sheath having at least one opening formed therein in front of said vertical flange to expose said flat face, an anchor body disposed in said opening, the forward side of said anchor body including a lading strap receiving bar, said anchor body having a recess formed therein beneath said bar and extending to opposite sides of the bar, a base member fixed to the flat face of said vertical flange and extending laterally outwardly of said vertically extending edges, the opposite lateral portions of said base member defining tab portions, said body having formed on the lateral portions of the rear side thereof oppositely directed tab portions extending inwardly toward each other, each of said body tab portions having a surface facing toward the forward side of said anchor body for engaging the rear surfaces of the tab portions of said base member, said anchor body having a surface formed thereon facing the rear side of said anchor body, said last mentioned surface being parallel to and spaced from said surfaces on the body tab portions and forming a bearing surface for maintaining the tab portions of said body in engagement with the tab portions on the base member, the tab portions on said body and said column having a vertical dimension substantially equal to that of a wall board, the tab portions on said body being slidable in a vertical direction and being interlocked with the tab portions fixed to said column such that said forward side of the anchor body is substantially flush with the faces of the adjacent wall boards, said body means also having formed along the opposite lateral portions thereof flanges extending outwardly away from the center of said body at the forward side of the body and flanges extending outwardly away from the center of said body at the rear side of the body, said flanges defining along each lateral portion of said body a pair of spaced oppositely facing surfaces substantially parallel to one another, said spaced oppositely directed surfaces along each lateral portion of said body means engaging oppositely directed faces of an associated wall board, the associated wall board having a recessed portion formed therein for receiving the associated outwardly extending flange of the anchor body whereby the anchor body fits substantially flush with the face of the associated wall board.
